UNITED STATES PATENT OFFICE.

MAX L. KAUFMANN, OF NEW YORK, N. Y.

DESIGN FOR A BASE-BALL SCORER.

42,361.

Specification for Design. Patented Mar. 26, 1912.

Application filed December 29, 1911. Serial No. 668,529. Term of patent 3½ years.

To all whom it may concern:

Be it known that I, MAX L. KAUFMANN, a citizen of the United States, and a resident of the borough of Manhattan, city, county, and State of New York, have invented a new, original, and ornamental Design for Base-Ball Scorers, of which the following is a specification.

Reference is had to the accompanying drawings in which—

Figure 1 is a view of one side of the scorer embodying the new design; Fig. 2 is a view of the other side thereof; and Fig. 3 is an edge view of the same.

The design comprises a top and bottom surface resembling generally in shape and appearance a manufactured smoker's product such as a cigar. The curved projections *a* are visible when the article is seen resting

on a flat surface. The apertures *b* are shown as located at one side of the longitudinal axial line of the article. The apertures *c* are illustrated as located on the other side of said axial line. Through these apertures a series of figured surfaces *d* are visible.

The complete design comprises a scorer of pleasing form and ornamental appearance.

I claim:

The ornamental design for a base ball scorer as shown and described.

In testimony whereof, I have hereunto set my hand in the presence of two subscribing witnesses.

MAX L. KAUFMANN.

Witnesses:

ERNST WALKORTZ,
FREDERICK RATH.
